PRICE MARKING TICKET

Harry G. Balthasar, West Tower Park, Ohio, assignor, by mesne assignments, to The Sprayomatic Products Company, Cincinnati, Ohio, a corporation of Ohio

Application December 15, 1937, Serial No. 179,974

10 Claims. (Cl. 40—23)

This invention relates to price marking tags or tickets and to means for securing the same to merchandise. More particularly, the invention relates to tags or tickets adapted to be attached to greeting cards or the like.

The structure of a price tag for use on a greeting card and the attachment of the price tag thereto involve problems entirely different from those attendant the construction of a price tag for use on other types of merchandise, such as garments and the attachment of the price tag thereto. The fine paper and artistic designs embodied in greeting cards would be damaged if the card were at all marked. This type of merchandise must be absolutely perfect in order to be saleable. It has been found in the past that the application of price tags to greeting cards, through the use of the customary clips, indented or otherwise marked the edge of the card.

It has been the object of the present inventor to provide a price marking tag or ticket adapted to be applied to flat merchandise, such as greeting cards or the like. This tag can be readily applied to the edge of the merchandise without marking the card in any way, and, at the same time, it employs a metal clip structure which provides the holding action requisite for maintaining the price ticket in place without contact of the metal with the card.

It has been a further object of the present inventor to provide these tickets so that they may be stacked either loosely in cartons, which may be readily inserted in a dispensing machine for dispensing the tickets directly from the cartons, or in continuous strip form which may be readily inserted in the magazine of a dispenser for delivery to an attachment point and with respect to a cut-off knife active for severing each ticket as it is applied.

The concept resulting from these objectives, generally speaking, takes physical form in a folded paper structure adapted to engage over the edge of the greeting card and including as a fixed part of the ticket, a metal clip, which imparts a holding force to the ticket sufficient for holding it in place upon the greeting card without contact of the metal with the card. The tickets, in gang strip length, are folded somewhat after the manner of the pleats of an accordion.

Other objects and advantages will be more fully apparent from the drawing, in which:

Figure 1 is a front view of the price marking ticket of this invention, showing it applied to a greeting card.

Figure 2 is a sectional view taken on line 2—2, Figure 1.

Figure 3 is a side view of a portion of a strip of tickets.

Figure 4 is a view taken similar to Figure 3, but showing the accordion pleated strip of tickets drawn out and for illustrative purposes, a portion in section.

Figure 5 is a sectional view taken on line 5—5 of Figure 4.

Figure 6 is a sectional view taken on line 6—6 of Figure 4.

Figure 7 is a front view of a modified form of ticket.

Figure 8 is a sectional view taken on line 8—8 of Figure 7.

Figure 9 is a perspective view of the ticket and the metal clip showing them separated.

Figure 10 is a sectional view taken on line 10—10 of the clip of Figure 9.

Referring to the drawing, the individual tickets, one of which is shown at 35, consists, in each instance, of an overlapped or folded piece of heavy paper or cardboard, providing flaps 36—36. One or both flaps may contain the price information shown at 37.

The metal clip, indicated at 38, consists of a strip of metal folded upon itself and engaged over the folded edge of the ticket. This clip is indented on both exposed faces, as at 39. The indentations may be a little off center relative to one another, as shown in Figure 2, so that a better gripping action is imparted to the card to be marked. Accordingly, when the greeting card, indicated at 40, is inserted between the flaps of the ticket, the gripping or spring action of the clip on the ticket fixes the ticket to the greeting card.

The clip may include slightly inturned inner edges 41 (see Figure 10) adapted to be imbedded in the ticket to provide greater friction for holding the clip in position.

As shown in Figures 3 to 6 inclusive, the tickets may be provided in continuous strip form. That is to say, instead of being cut up into individual tickets, an accordion pleated strip 43, with metal clips engaged over the folded edges along one side of the strip, is provided. This gang strip may be used in an appropriate machine provided with a knife to sever the individual tickets from the gang as they are applied to the greeting card. Such a machine is disclosed in the copending application, filed February 2, 1940, Serial No. 317,040.

Figures 7, 8, and 9 disclose the single ticket;

that is, one which is a separate unit and is not provided as part of a strip. This single type ticket, indicated at 44, may have its rear flap shorter than the front flap to facilitate insertion of the greeting card between them.

Either type, the gang strip or the single tag, may be provided with the guide notches 45—45 shown in Figures 7 and 9. The guide notches serve to align the tags when they are stacked 10 in the magazine of a card dispensing machine.

Having described my invention, I claim:

1. A price marking ticket assembly, comprising, a strip of heavy paper, accordion pleated, and metal clips engaged over the folds of the paper along one side of the strip.
2. A price tag comprising, a folded strip of paper material, and a folded strip of metal, said strip of metal engaged over the folded edge of the strip of paper and including means for preventing easy detachment.
3. A price tag for greeting cards or the like, consisting of a folded strip of material bearing printing, and a folded strip of flexible strip material engaged over the folded edge of the first mentioned strip of material and including indented portions engaging the first mentioned strip of material for preventing easy detachment therefrom, said price tag attachable to the greeting card merely by engagement over the edge thereof.
4. A price tag for a greeting card or the like, comprising, a folded strip of paper material, a folded strip of metal engaged over the folded edge of the strip of paper material, and indentations in said metal strip engaging said paper material.
5. Price marking tickets, comprising, a strip of accordion pleated paper, metal clips engaged over the folds of the paper along one side of the strip, one flap of each ticket including a clearance notch in the outer end of the flap adjacent the fold connecting the respective tickets opposite to the folds carrying the clips.
6. A price marking ticket assembly, comprising, a strip of accordion pleated paper, metal

clips engaged over the folds of the paper along one side of the strip, notches in the side edges of the series of tickets thus formed, one flap of each ticket including a notch in the outer end of the flap and adjacent to the fold connecting the respective tickets opposite to the fold carrying the clip.

7. A tag comprising a strip folded upon itself to clasp over a margin of the goods to be tagged, and a correspondingly formed sheet metal clip 10 clasped over the folded edge of the tag, the lapped portions of said clip including burred inner edges adapted to penetrate into the tag material to secure the clip in place thereon.

8. An article of manufacture comprising, a 15 strip lapped or folded upon itself in continuous zig-zag formation, each pair of lapped portions having a metal clip clasped over the folded edges thereof forming a plurality of tags, each of which is joined along the opposite folded edges of said 20 lapped portions, said strip adapted to be severed along said joined portions.

9. An article of manufacture comprising, a strip lapped or folded upon itself in continuous zig-zag formation, each pair of lapped portions 25 engaged by one of a plurality of clips along one side of said zig-zag strip, each of said clips comprising a metal strip folded upon itself to clasp over the folded edge of each pair of lapped portions forming a plurality of tags, each alternate 30 fold including a notch at the opposite side of said zig-zag strip terminating along the line of fold of said strip, each successive tag being joined by the material remaining on opposite sides of said 35 notch.

10. A strip of paper providing a series of price marking tickets, said strip of paper divided into sections folded upon themselves, metal clips engaged over the folds of the sections along one side of the strip, one flap of each section including a 40 clearance notch in the outer end of the flap adjacent the fold connecting the respective sections opposite the folds carrying the clips.

HARRY G. BALTHASAR.
